UNITED STATES PATENT OFFICE.

DANIEL NETTEKOVEN, OF FORT SHAW, MONTANA TERRITORY.

WATCH-PENDANT KEY.

SPECIFICATION forming part of Letters Patent No. 352,257, dated November 9, 1886.

Application filed July 1, 1886. Serial No. 206,815. (No model.)

To all whom it may concern:

Be it known that I, DANIEL NETTEKOVEN, of Fort Shaw, in the county of Lewis and Clarke and the Territory of Montana, have invented a new and Improved Watch-Winding Mechanism, of which the following is a full, clear, and exact description.

The object of my invention is to provide a new and improved watch-winding mechanism which will prevent the operator from breaking parts of the watch if he continues to turn the winding mechanism after the watch is wound up.

The invention consists of a tension-clutch on the winding mechanism, and of a device for regulating the tension of the clutch.

The invention also consists of various parts and details and combinations of the same, as will be fully described hereinafter, and then 20 pointed out in the claims.

Reference is to be had to the accompanying drawings, forming a part of this specification, in which similar letters of reference indicate corresponding parts in all the figures.

25 Figure 1 is an elevation of a watch-key provided with my improvement. Fig. 2 is a sectional elevation of the same. Fig. 3 is an elevation of a stem-winder provided with my improvement. Fig. 4 is a front elevation of 30 a modified form of winder. Fig. 5 is a bottom view of the spring of the modified form shown in Fig. 4. Fig. 6 is a face view of a ratchet of a modified form. Fig. 7 is an end elevation of the same. Fig. 8 is a sectional elevation of 35 a modified form of improvement. Figs. 9 and 10 are detail views of the same. Fig. 11 is a face view of a ratchet-wheel of a modified form, and Fig. 12 is an end elevation of the same.

40 My invention is attachable to watch-keys and stem-winders, as illustrated in the drawings, the mechanism being the same for both forms of watch-winders.

The winding mechanism or key A is provided with the shank B, having the square 45 square C, which engages with the square pin attached to the pinion meshing into the main shaft of the winding mechanism. The shank B is a ratchet-wheel, D, having notting edges, as shown in Fig. 6, the teeth may have flat 50 s, as illustrated in Figs.

6 and 7. The ratchet-wheel D meshes into a corresponding ratchet-wheel, E, formed on the bottom of the hollow stem F, which is provided either with plain straight or fluted sides H, or with a spherical fluted knob, H', as shown in Figs. 3 and 4, of any approved construction. The ratchet-wheel E forms, in conjunction with the ratchet-wheel D, the 60 clutch of the winding mechanism.

From the center of the ratchet-wheel D projects a shaft, G, which passes into and has its bearing in the hollow stem F, and on it is coiled a spring, I, one end of which rests on the bottom of the stem F, the other end resting against a cam, J, adapted to slide on the shaft G, and pressed against the spring I by a nut, K, screwed on the upper screw-threaded end of the shaft G. A cap, L, fits over the upper 70 open end of the hollow stem F, and prevents dust, &c., from entering the stem F. The shaft G is preferably made square or hexagonal in cross-section below the screw-threaded part, and a corresponding aperture, which is 75 square or hexagonal in cross-section, is formed in the sliding collar J, so that the latter turns with the shaft G, and can slide on the same without loosening the nut K.

80 The operation is as follows: The spring I holds the ratchet-wheels D and E in contact, and the tension of the spring is regulated by screwing the nut K up or down. The tension must be sufficient to hold the wheels D and E in contact when the watch is being wound—85 that is, when the operator turns the stem F in a forward direction, and as soon as the winding of the watch is accomplished, the shank B remains stationary, even if the operator continues to turn the stem, while the stem F and 90 its ratchet-wheel E turn, and the latter glides over the stationary ratchet-wheel D, which prevents the breaking of the mainspring or of the other parts of the watch. The stem may also be turned backward at any time, 95 which backward movement causes the ratchet-wheel E to glide over the wheel D, as the shank B remains stationary. For stem-winders I may also use the construction shown in Fig. 4, in which I provide the stem F with the 100 square part N, which passes through an elongated slot, O, in the spring P, which is attached to the edge of the watch in any suitable manner, and the tension of the spring on the
